UNITED STATES PATENT OFFICE.

JAMES A. SMITH, SR., OF ST. LOUIS, MISSOURI.

DESIGN FOR AN ICE-MOLD.

SPECIFICATION forming part of Design No. 22,298, dated March 14, 1893.

Application filed February 4, 1893. Serial No. 461,066. Term of patent 14 years.

To all whom it may concern:

Be it known that I, JAMES A. SMITH, Sr., a citizen of the United States, residing at St. Louis, in the State of Missouri, have invented and produced a new and original Design for Ice-Molds; and I do hereby declare the following to be a full, clear, and exact description of the same, reference being had to the accompanying drawings, forming a part thereof.

Figure 1, represents a perspective view showing my design. Fig. 2 is a vertical longitudinal sectional view. Fig. 3 is a transverse sectional view and Fig. 4 is a longitudinal sectional view taken on line z, z , Figs. 2 and 3.

This design of a mold is intended more particularly for the manufacture of artificial ice.

The leading feature of my new design consists in the mold with hollow ribs on each side and ends, and bottom, the surfaces between these ribs present a plane when viewed in plan as in Fig. (4) of the drawings, representing an irregular shape, showing depression inside causing ridges outside.

The sides and ends of the mold extend outwardly and upwardly from the bottom, bell-shaped; the ribs are likewise tapering from bottom to top and being widest at the top.

The letter "A," represents the mold, and "A'" "A'," the ridges thereof which project outwardly from the walls "B B," providing a continuous rectangular shape both on the inner as well as the outer surfaces.

"C" is the bottom of the mold, the inside and outside surfaces thereof are planes, except that a depression or rib "C'," extends from end to end of the bottom of the mold as shown in Figs. (2) (3) of the drawings.

What I claim is—

The design for an ice mold herein described and shown.

In testimony whereof I affix my signature in presence of two witnesses.

JAMES A. SMITH, SENIOR.
